UNITED STATES PATENT OFFICE.

LOUIS R. PARSONS, OF RARITAN, ILLINOIS.

RAIL AND TIE PLATE THEREFOR.

Application filed April 18, 1925. Serial No. 24,093.

To all whom it may concern:

Be it known that I, LOUIS R. PARSONS, a citizen of the United States, residing at Raritan, in the county of Henderson and 5 State of Illinois, have invented certain new and useful Improvements in a Rail and Tie Plate Therefor; and I do declare the following to be a full, clear, and exact description of the invention, such as will enable others 10 skilled in the art to which it appertains to make and use the same.

This invention relates to an improved track rail and tie plate therefor, and the present application constitutes a continuation 15 in part of my U. S. application Serial No. 750,391, filed Nov. 17th, 1924.

Like the device shown in the application just referred to, the present invention includes a socket in the bottom of a track rail, 20 a tie plate upon which the rail rests, and a lug on the tie plate for snug reception in the socket, and one object of the invention is to not only so shape the inter-engaging socket and lug, as to effectively guide the rail back 25 to its proper place on the tie plate under vibration of the rail but to also so form the socket in the base of the rail as to prevent material weakening of the latter, thus obtaining the maximum bearing surface with 30 the minimum reduction in the moment of inertia.

The socket in the rail extends transversely of the web thereof, that is, has its maximum dimension transverse the rail with a plain 35 upper guiding surface of appreciable width which extends from the mid-length or deepest point of the socket in gradual curvature to a substantial mergence with the bottom surface of the rail. The side walls of the 40 socket are slightly convergent upwardly and merge on a slightly rounded line with the plain top surface of the socket. The lug on the tie plate is of course exactly complementary to the formation of the socket, so that 45 the lug when in place in the socket presents its maximum obstruction toward a creeping action of the rail and its minimum obstruction toward a lateral movement of the rail. As the lug has its main length or dimension 50 transverse the rail, the guiding influence of the surface of the lug transverse the rail is gradual, while the more abrupt side walls of the lug present a greater restraining influence against creeping. The extreme upper 55 surface of the lug, by reason of the formation described, is directly in line with the

web of the rail, and the divergence from this surface which is gradual transverse the rail web, and more abrupt longitudinally of the rail web, effectively combines the guiding re-positioning of the rail when laterally displaced under strain, and at the same time, a guiding but more resistive influence against creeping of the rail.

The socket in the rail extends in both directions beyond and transversely of the rail web, but does not extend to the edges of the rail flange, so that the socket is wholly within the outline of the rail base. The upper wall of the socket which forms the guiding 65 surface extends in both directions transversely of the rail web from the central line of the socket, which is its point of maximum depth and is in direct line with the web of the rail. The curvature of the guiding surface from this center point is outwardly toward the bottom surface of the rail and finally merges into such surface. By this construction, the depth of the socket gradually decreases throughout that portion 70 thereof located beyond the rail web, that is, in the flange portion of the rails, so that the minimum amount of metal is cut from these flanges in forming the socket. Thus, any 75 material weakening of the flange portions of 80 the rail is avoided.

Another object of the invention is to provide a tie plate provided with a rib spaced laterally from its lug to engage the edge of one base flange of the rail when the lug and 85 socket are in co-operation.

A further object is to provide a rail and tie plate of the character set forth, which will not only be effective for the intended purposes but on account of ease and cheapness of manufacture and extreme simplicity of construction will be commercially feasible.

With the foregoing in view, the invention resides in the novel subject matter herein-after described and claimed, the description 90 being supplemented by the accompanying 95 drawings.

Figure 1 is a side elevation partly in section showing the rail, the tie plate and a tie 100 in operative relation.

Figure 2 is a vertical transverse sectional view as indicated by line 2-2 of Fig. 1.

Figure 3 is a perspective view of a portion of the rail.

Figure 4 is a perspective view of the tie 110 plate.

Figure 5 is a plan view showing a form

of tie plate in which a plurality of lugs are used instead of only one.

Figure 6 is a broken perspective view, showing the lug enlarged.

5 In the drawings above briefly described, R designates a conventional form of track rail having the usual web W and base flanges F, which flanges are thickened toward their lines of juncture with the web 10 W, in the usual way. Formed in the bottom of the rail R by a rolling operation or otherwise, are longitudinally spaced sockets 1, and as they are all of the same form, only one will be described. This socket is horizontally elongated in a direction transverse to the rail web W, and while its ends extend into the base flanges F, said ends terminate inwardly of the edges of said flanges. The socket 1 is shallow and it is provided 15 with an arched upper or guiding surface 2 which is preferably formed on the arc of a circle. This upper surface merges into the lower surface of the rail R, inwardly of the edges of the flanges F. The side walls 3 of 20 the socket 1, are straight or flat and they converge upwardly to a slight extent, as shown in Fig. 1. It is to be particularly noted that the maximum depth of the socket is in direct alinement with the web of the 25 rail, at which point of course the base portion of the rail is of maximum strength. From this point of maximum depth, that is to say, from points in line with the sides of the web, the upper or guiding surface of the 30 socket, by reason of its curved formation is of gradually and continually reduced depth until it finally merges into the bottom surface of the flange. Thus, as the socket extends into the flange portion of the rail, it 35 is of decreasing depth outwardly, thereby necessitating the removal of these portions of the socket, with the result that any material weakening of the base flanges is avoided. 40

45 By forming the sockets 1 in the manner shown and described, only an infinitesimal weakening of the rail is produced, and in actual tests, carrying a load up to 150,000 pounds, it is found that a rail constructed in accordance with the invention will deflect considerably less than two per cent more than an ordinary solid rail of the same size and material. Thus, it will be seen that this amount of weakening is negligible as compared with the weakening necessarily produced by arrangements of somewhat similar devices heretofore proposed in the art. By shaping the sockets and the co-acting lugs on the tie plates in the manner disclosed, 50 the maximum bearing surface is obtained with the minimum reduction in the moment of inertia.

55 Usable with the improved rail, is a tie plate 4 which is preferably of rectangular form and provided on its lower surface with

ribs 5 to engage an ordinary tie T. Along one edge, the plate 4 is provided with a rib 6 which is adapted to abut the edge of one of the base flanges F, when the rail is in operative relation with the plate, and spike 70 holes 7 have been shown in the plate, two of said holes extending through this rib. The upper surface of the plate 4 is provided with an integral lug 8 of a size and shape identical with the size and shape of any of the sockets 1, so that it may be tightly received in the latter, to contact with all surfaces thereof. On account of this identity in shape, between the sockets 1 and the lug 8, the latter will not be further described. 75 Obviously, any lower surface of the rail, whether the lower surface of one of the flanges F, or one end portion of one of the surfaces 2, will have a tendency to co-operate with the guiding surface, thus assisting in laterally shifting the rail into place. When this shifting is effected, if the lugs 8 of the numerous tie plates, are not immediately received in the sockets 1 of the rail, it is only necessary to longitudinally shift the plates to a slight extent, whereupon the proper interfitting of lugs and sockets will take place. The spikes are now driven, and the rail is thus securely anchored to the ties, 80 both against longitudinal creeping and lateral shifting. In case of loosening of any of the spikes, permitting slight vertical movement of the rail R during the passage of trains thereover, the shaping of the co-acting lugs and sockets, will effectively return the rail to its proper contact with the tie plates. Moreover, this formation of lugs and sockets provides for maximum bearing surface, with the minimum reduction in the 85 moment of inertia.

90 In some instances, instead of providing the tie plate with only one lug, it may be provided with a plurality of such lugs. This construction is disclosed in Fig. 5, in which 4^a designates the tie plate and 8^a refers to 95 a number of lugs thereon, corresponding in size and shape to the lug 8 above described and properly spaced for reception in a number of the sockets 1.

100 Excellent results are obtainable from the details disclosed and they are therefore preferably followed. However, within the scope of the invention as claimed, minor changes may of course be made.

105 I claim:

110 1. The combination with a track rail having formed in its bottom surface a socket arranged transverse the web of the rail with its ends extending into but terminating short of the edges of the base flanges of the 115 rail, the ends of the socket being formed to prevent undue weakening of the base flanges of the rail beyond the web, and a tie plate formed with a lug to fit in said socket, with the wall of the lug arranged at other than 120

a right angle relation to the plate for guiding influence on the rail.

2. The combination with a track rail having formed in its bottom surface a socket arranged transverse the web of the rail with its ends extending into but terminating short of the edges of the base flange of the rail, the ends of the socket being formed to prevent undue weakening of the base flanges of the rail beyond the web, and a tie plate formed with a lug to fit in said socket, with the walls of the lug arranged at other than a right angle relation to the plate for guiding influence on the rail, the tie plate being formed with a rib extending longitudinally thereof to form an abutment for the free edge of one of the rail flanges when the socket in said rail is in co-operation with the lug on the plate.

3. The combination with a track rail having formed in its bottom surface a socket, with its maximum dimension transverse the rail, the upper wall of the socket being gradually curved in both directions from the area in line with the rail web, the side walls of the socket being in part convergent and merging in conforming curvature into the upper wall of the socket, of a tie plate having a lug thereon of complementary formation to that of and adapted to fit within the socket, whereby to provide a guiding influence on the rail in its return to normal position after lateral displacement strain and a combined resistive and guiding influence on the rail under a creeping tendency of the rail.

4. A tie plate for railroad rails, comprising a plate section adapted to underlie the rail and formed within the rail area with a lug having its maximum dimension transverse the web of the rail and its maximum projection beyond the surface of the plate in line with the web of the rail, the upper surface of the lug being plain and gradually curving from that area adapted to underlie the rail web in both directions toward and substantially merging into the surface of the plate, the side walls of the lug converging from the surface of the plate with their upper edges merging into the upper surface of the lug, and a rail formed with a socket shaped to correspond with and

receive the lug on the plate, whereby the rail under lateral strain will be guided for a return to normal position and under creeping strain will be resisted by the side walls and guided under creeping displacement by the area of such side walls merging into the top wall.

5. A tie plate for railroad rails, comprising a plate section adapted to underlie the rail and formed within the rail area with a lug having its maximum dimension transverse the web of the rail and its maximum projection beyond the surface of the plate in line with the web of the rail, the upper surface of the lug being plain and gradually curving from that area adapted to underlie the rail web in both directions toward and substantially merging into the surface of the plate, the side walls of the lug converging from the surface of the plate with their upper edges merging into the upper surface of the lug, and a rail formed with a socket shaped to correspond with and receive the lug on the plate, the tie plate being formed with a rib extending longitudinally thereof to form an abutment for the free edge of one of the rail flanges when the socket in said rail is in co-operation with the lug on the plate.

6. A rail having a socket formation in its lower surface in line with and extending in both directions beyond and transversely of the rail web, with the socket terminating short of the edges of the rail flange, the socket having its maximum depth in line with the rail web and having a guiding surface extending transversely of the rail web and curving from the point of maximum depth of the socket to and curving from the point of maximum depth of the socket to and merging with the lower surface of the rail, the curvature of such guiding surface beyond the rail web being such that the resultant depth of the socket will avoid weakening the flanges of the rail beyond the web, and a plate provided with a lug shaped to correspond to and fit within the socket of the rail.

In testimony whereof I have hereunto affixed my signature.

LOUIS R. PARSONS.
